Atty.

UNITED STATES PATENT OFFICE

JOHN M. DAVIDSON, OF DULUTH, MINNESOTA

WIRE SECURING CLIP

Application filed May 2, 1928. Serial No. 274,656.

This invention relates to a new and improved wire securing clip, and more particularly to a clip of the type adapted for use in securing fence wires to metallic fence posts.

3 Metallic fence posts are coming into general use and with such posts there is the necessity for clips or similar devices for securing the wires to the post. Short lengths of wire have been used for this purpose but 10 require considerable labor for their application and tools for properly twisting the ends together. Other forms of clips have been developed, formed from heavy wire and having ends or prongs which are bent in place 15 by hammering. The posts are light and resili- 20 silent and it is difficult to satisfactorily hammer clips in place upon them.

It is an object of the present invention to provide a new and improved clip adapted to 25 be easily and quickly put in place without the use of special tools.

It is a further object to provide a clip which may readily be manufactured with usual forms of wire working machines.

25 It is also an object to provide a clip which affords a firm grip upon the wire being secured.

Other and further objects will appear as the description proceeds.

30 I have illustrated one preferred form of my invention in the accompanying drawings, in which

Figure 1 is a face view of a section of a fence post with my clip securing a wire there- 35 to;

Figure 2 is a view of Figure 1 as seen from the right;

Figure 3 is a horizontal section taken on line 3-3 of Figure 1;

40 Figure 4 is a perspective view of a clip with both loops in the unbent position; and

Figure 5 is a view similar to Figure 4 but with one securing loop bent to the securing 45 position.

The form of fence post shown in Figures 1 to 3 forms no part of the present invention and is merely shown for the purpose of illustrating the application of my improved clip.

50 The clip may be used with other forms of

metal posts, and may also be used with concrete or wooden posts.

The post shown has the rear portion 11, the side portions 12 and the serrated edges 13. The wire 14 has been shown as resting 55 between two serrations against the edges 13.

My improved clip comprises the body portion 15, the side arms 16 and the securing loops 17. The ends 18 of the loops are bent around the main portion of the wire to afford 60 a strong construction. The present device therefore results in a clip having a body portion and arm portions which are straight and which lie in the same plane, with securing loops depending from the arm portions at substantially right angles thereto. The clip may be made in the form shown in Figure 4 with both loops extending downwardly or in the form shown in Figure 5 with one loop bent in hook formation. 70

The form of Figure 4 is applied by placing the wire against the front of the post, placing the hook against the back of the post and moving it downwardly until the loops 17 engage the wire. With the clip properly sized 75 and the loops inclining inwardly slightly, the resilience of the clip will hold the clip and wire in place. To make a permanent connection, each loop 17 is then bent around the wire to the position clearly shown in Figure 2. This may be readily accomplished by 80 inserting a pointed tool into the loop which may be easily and quickly bent around the wire.

The form of construction shown in Figure 85 5 is applied in a generally similar manner. The reversely bent loop is first hooked over the wire, the clip swung around behind the post and the other loop hooked over the wire. 90 The second loop is then bent around the wire. The first loop may be left as it is or may be tightened up against the wire.

The loop ends on the clips afford a ready purchase for any pointed tool so that the 95 clips may be readily and quickly bent to securing position. These loops also afford a firm and positive double grip upon the fence wire. The holding strain is divided between the two wires and there is much less possi- 100

bility of the connection working loose than with an old type of single tie wire.

While I have shown one form of construction by way of illustration, my invention is capable of modification for use with different types of posts and to meet varying conditions, and I contemplate such changes and modifications as come within the spirit and scope of the appended claims.

10 I claim:

1. A wire attaching clip having a body portion, a wire engaging hook carried at one end of the body portion, and a closed wire engaging loop portion carried at the other end of the body, said loop portion being bendable by means of a tool inserted within the loop to form a hook.
2. As an article of manufacture, a wire attaching clip having a body portion and a plurality of arm portions adapted to encircle a support, and wire engaging loop portions formed at the extremity of the arms, said loop portions being bendable to apply clamping pressure to the wire engaged thereby.

25 Signed at Duluth, Minnesota, this 21st day of April, 1928.

JOHN M. DAVIDSON.
